UNITED STATES PATENT OFFICE

JOHN H. DU RALL, OF MOUNDS, ILLINOIS

HONEY CONTAINER

Application filed October 29, 1928. Serial No. 315,785.

This invention relates to containers especially adapted for use in the sale of honey, an object being to provide a container which will closely simulate the hive of a bee, and which may be made in sizes to be packed compactly for shipment, the dimensions of the containers with respect to the dimensions of the cartons in which they are packed, providing for different combinations of sizes in a single carton.

Another and important object of the invention is the provision of a container which, after it has served for the sale of its original contents, may be useful to the purchaser for other purposes and thus aid in the sale of the original goods and if desired provide an advertising medium.

With the above and other objects in view, the invention further includes the following novel features and details of construction, to be hereinafter more fully described, illustrated in the accompanying drawings and pointed out in the appended claims.

In the drawings:—

Figure 1 is a perspective view of one of the containers.

Figure 2 is a section on the line 2—2 of Figure 1.

Figure 3 is a section on the line 3—3 of Figure 2.

Figure 4 is an enlarged fragmentary sectional view taken substantially on the line 2—2 of Figure 1 and illustrating the manner of locking the false cover in position.

Figure 5 is a top plan view of the container with the false cover removed.

Figure 6 is a fragmentary sectional view showing the manner of attaching the handle or bail to the container.

Figure 7 is an enlarged elevation of the combined cover securing means and bail retainer.

Referring to the drawings in detail where in like characters of reference denote corresponding parts, the reference character 10 indicates a container which is especially designed for containing honey, and it is the purpose of the invention to make these containers in different sizes so as to hold different amounts of honey. It is also proposed that

the dimensions of the containers be such that various different combinations of sizes may be packed within a carton.

The container is provided with a sealed top or cover 11 which is provided with a discharge spout 12 normally covered with a cap 13.

One of the important objects of the invention is to render the container useful after its contents have been removed and for this purpose there is provided a false cover 14 having a flange 15 which extends downwardly over the upper edges of the container. This cover is provided with a raised portion 16 which provides a compartment 17 into which the discharge spout 12 extends. This compartment also houses a bail 18 having in-turned ends 19.

The bail is normally housed within the compartment and after the goods are sold, is removed and attached to the container. For this purpose, the container is provided at each end with an offset strap 20 having an opening 21 therein. These openings are adapted to receive in-turned extremities 19 of the bail as will be readily understood.

In order to removably retain the false cover 14 in place the strap 20 is provided with an extension or tongue 22 whose upper free end is bent inward so as to extend within an opening 23 provided at each end of the false cover 14. When it is desired to remove the cover 14, the extension or tongue 22 is bent outward to the position shown in Figure 6 of the drawings. The outer extremity of the tongue 22 is notched as shown at 24 and this notch is adapted to receive the bail 18 so as to hold the latter in an upright position as shown in Figure 6. When the original contents of the container have been removed, the top 11 may be cut on the line indicated at *a* in Figure 5 of the drawings so as to provide an open top container which may be closed when desired by the false cover 14.

The invention is susceptible of various changes in its form, proportions and minor details of construction and the right is herein reserved to make such changes as properly fall within the scope of the appended claims.

Having described the invention what is claimed is:—

1. In a container, a false cover spaced above the top of the container and defining a compartment adapted to contain a detachable handle, means at opposite ends of the container for removable engagement with the handle, and combined means extending from the handle engaging means to detachably engage the false cover and to provide a support for the handle.
2. In a container, a false cover spaced above the top of the container and defining a compartment, said cover having openings in opposite ends, an offset strap secured to each end of the container and having an opening therein, a bail normally housed within the compartment and adapted to have its opposite ends engaged within the openings of the straps, tongues extending from the straps for engagement within the openings to removably hold the false cover in place, and said tongues having notches in their free ends to engage the bail and hold the latter in an upright position when said bail is attached to the strap.

In testimony whereof I affix my signature.
JOHN H. DU RALL.
